(57) **CLAIM**

The ornamental design for a snow bike, as shown and described.

DESCRIPTION

FIG. 1 is a front left perspective view of the snow bike of the present invention;

FIG. 2 is a rear left perspective view of the snow bike of the present invention;

FIG. 3 is a front right perspective view of the snow bike of the present invention;

FIG. 4 is a rear right perspective view of the snow bike of the present invention;

FIG. 5 is a left side elevation view of the snow bike of the present invention;

FIG. 6 is a right side elevation view of the snow bike of the present invention;

FIG. 7 is a top view of the snow bike of the present invention;

FIG. 8 is a rear view of the snow bike of the present invention;

FIG. 9 is a bottom view of the snow bike of the present invention; and,

FIG. 10 is front left side view of an alternate embodiment of the snow bike of the present invention.

1 Claim, 10 Drawing Sheets
